UNITED STATES PATENT OFFICE.

HENRY E. HOOVER, OF KINSEY, MISSOURI.

CLOTHES DRIER.

Application filed April 11, 1924. Serial No. 705,756.

This invention relates to improvements in clothes driers and more particularly to that type designed for back yard use.

An important object of the invention is to provide a clothes drier wherein the clothes line may be raised or lowered as desired by the user.

A further object of the invention is to provide a clothes drier which may be operated without great effort and greatly assist in the drying of the clothes.

A still further object of the invention is to provide a device of this character which is comparatively simple, yet durable in construction and efficient for the purpose intended.

Other objects and advantages of this invention will be apparent during the course of the following description.

In the accompanying drawings forming a part of this specification and in which like numerals are employed to designate like parts throughout the same:

Figure 1 is a side elevation of my assembled device,

Figure 2 is a top plan view of the same,

Figure 3 is an enlarged top plan view of the operating mechanism,

Figure 4 is an enlarged detailed view of the line carrier,

Figure 5 is a fragmentary vertical section taken on line 5—5 of Figure 2.

In the drawings, the numerals 10 and 10' indicate upright posts having their lower extremities embedded in the ground and preferably formed of T iron. The post 10 carries the operating mechanism which consists of a rectangular frame 11 secured to the post by means of knees 12 and having drums 13 and 13' rotatably mounted therein. The shaft of the drum 13 carries a worm wheel 14 which meshes with a worm 15 carried by a shaft 16. The shaft 16 is positioned in brackets 17 and 18 and is disposed at an angle inclined with relation to a horizontal line. The brackets 17 and 18 are provided with bearings 19 and 20 which receive the shaft 16. Collars 21 are provided upon the shaft to prevent longitudinal displacement thereof with relation to the bearings. A handle 22 is carried at the lower end of the shaft 16 for rotating the same. The shaft of the drum 13' carries a gear wheel 23 which is located at the opposite side of the frame from that side at which the worm wheel 14 is located. A similar gear wheel 24 is car-

ried by the shaft of the drum 13 and meshes with the gear 23.

Brackets 25 are mounted at the upper end of the post 10 and three pulleys are journaled between the said brackets, the same being designated by the numeral 27. Collars 28 are interposed between the pulleys 27 for holding the same in spaced positions. Brackets 29 are mounted at the upper end of the post 10 and have a pair of pulleys 31 journaled therebetween, said pulleys 31 being spaced from each other by a collar 32. Each of the posts 10 and 10' also has journaled at the lower portion thereof a pulley 33.

Carriers 36 are slidably mounted upon the intermediate portions of the posts 10 and 10' and each consists of a U-shaped frame 37 having a roller shaft 38 extending across said frame which is held in position by pins 39. A roller 40 is journaled upon each of the shafts 38. A pair of oppositely disposed stub shafts 41 are mounted near the outer extremities of each of the frames 37 and carry a pair of rollers 42 mounted upon the shafts and adapted to engage the sides of the posts, each of said frames also having a screw eye 43 carried thereby. A bracket member 37' is carried by each frame 37 and the frame arranged upon the post 10 carries an eye 43'. A spring 44 is secured to one of the eyes 43 and is connected with the line 44' which has its opposite end attached to the eye 43' carried from the frame arranged on the opposite post for the purpose of retaining the line in a taut condition.

A pair of wires or cables 45 and 46 are used for elevating or lowering the frames 37 on the posts 10 and 10'. The wire or cable 45 has one end thereof 45' attached to the eye 43' carried by the frame 37 arranged upon the post 10, said wire or cable 45 then being arranged about one of the pulleys 31 upon the upper end of the post 10 and then across and over one of the pulleys 27 on the post 10'. The intermediate portion of the wire cable 45 is wound about the drum 13, and has its opposite end portion extending upwardly and over another one of the pulleys 27 on the post 10', then across and over the other pulley 31 upon the post 10, from which said wire or cable 45 extends downwardly and under the pulley 33 on the post 10 from which said wire or cable extends upwardly and is attached to the eye 43' arranged upon the frame that is slidably

mounted on the post 10. From the foregoing, it can be seen that when the drum 13 is rotated that one end portion thereof will be wound upon the drum while the other end portion is unwound from the drum, thus causing the frame 37 on the post 10 to either be elevated or lowered. The cable 46 has one end thereof, as indicated by the numeral 46^a, attached to the eye 43 upon the frame 37 slidably mounted on the post 10', from which said wire or cable 46 extends upwardly and over a pulley 27 mounted upon the upper end of the post 10' and then downwardly and wound over the drum 13'. The other end portion of the cable 46 extends downwardly and under the pulley 33 on the lower portion of the post 10' and then upwardly and is connected to the eye 43 of the frame 37 carried by the post 10' as indicated by the numeral 46^b. It will also be noted that when the drum 13' is rotated that one end portion thereof is wound upon said drum while the other end portion is unwound from the drum, thus raising and lowering the frame 37 mounted upon the post 10'. As the drums 13 and 13' are geared together by means of the gears 23 and 24, one drum will be rotated upon rotation of the other so that both of the frames 37 will slide either upwardly or downwardly on the posts 10 and 10' so that both ends of the wire 44' will be elevated or lowered together.

In use, the device may be readily installed in a backyard of the ordinary dwelling house or any suitable place, and readily operated. When it is desired to hang the clothes upon the line the handle 22 is rotated causing similar rotation of the drums 13 and 13' unwinding certain end portions of

the wires or cables 45 and 46 and winding the other end portions of said wires or cables for elevating or lowering the wire 44'. After the clothes have been hung upon the line and the line firmly secured in position, the handle 22 is operated in the reverse direction and the line carrying the clothes elevated to the desired height thus retaining them out of reach of persons or animals and insuring their being dried without soiling.

It is to be understood that the form of my invention herewith shown and described is to be taken as the preferred example of the same, and that various changes as to the shape, size and arrangement of parts may be resorted to without departing from the spirit of the invention or the scope of the subjoined claim.

Having thus described my invention, I claim:

A clothes drier comprising spaced posts, pulleys journaled at the upper and lower portions of the posts, frames slidably mounted upon the posts between the pulleys, a clothes support connected with the frames and bridging the space between them and including a yielding element exerting pulling strain upon both of the frames, cables trained about the pulleys and connected with the frames, and winding mechanism mounted upon one of the posts, said cables being arranged to wind upon the winding mechanism and whereby the frames are positively moved along the posts simultaneously.

In testimony whereof, I have affixed my signature.

HENRY H. HOOVER
